FIREARM WITH SLING STRAP

Edwin Pugsley and Frederick L. Humeston, New Haven, Conn., assignors to Western Cartridge Company, New Haven, Conn., a corporation of Delaware

Application October 9, 1941, Serial No. 414,300

15 Claims. (Cl. 42—85)

The present invention relates to improvements in firearms and relates more particularly to improvements in firearms having sling-straps to enable the firearm to be slung across a person's shoulder and for other purposes of handling, etc.

One of the objects of the present invention is to provide a superior firearm having a sling-strap of simple and readily attachable and detachable character.

Another object of the present invention is to provide a superior firearm of the character referred to and in which the sling-strap is detachably retained in place by simple and effective means.

A further object of the present invention is to provide a superior firearm of the character referred to, in which the sling-strap is retained in place by means of a separable adjunctive device.

Still another object of the present invention is to provide a superior firearm-structure embodying both a sling-strap and a separable adjunctive device, and in which the adjunctive device referred to is releasably retained in assembled relationship with respect to the firearm-structure by means of the sling-strap.

A still further object is to provide a superior firearm having normally organized therewith a sling-strap and a separable adjunctive device (an oil can, for instance) useful in the care of the firearm, and in which firearm the said adjunctive device and the said sling-strap mutually serve to maintain each other in assembled relationship to the firearm.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of a firearm embodying the present invention;

Fig. 2 is a broken view in longitudinal section taken on the line 2—2 of Fig. 1;

Fig. 3 is a view corresponding to Fig. 2 but showing the sling-strap partly released from the butt-portion of the stock, preparatory to the complete disconnection of the rear end of the said sling-strap and the complete demounting of the oil can;

Fig. 4 is a broken view of the left side of the rear portion of the stock with the sling-strap in place thereon;

Fig. 5 is a corresponding view but looking toward the right side of the stock;

Fig. 6 is a transverse sectional view taken on the line 6—6 of Fig. 4;

Fig. 7 is an enlarged view in central longitudinal section of the oil can detached;

Fig. 8 is a broken perspective view of the rear portion of the buttstock, viewing the same mainly from the left side; and

Fig. 9 is a similar view but viewing the stock mainly from the right side.

The particular firearm herein chosen for purposes of illustrating the present invention includes, in the main, a stock 10, a receiver 11, a barrel 12 and a barrel-cap 13. The stock 10 and the barrel-cap 13 are preferably formed of wood or other suitable heat-insulating material while the receiver 11 and barrel 12 are preferably formed of high-grade steel.

The stock 10 is preferably formed in one continuous piece, but for convenience of description its forward portion, which mainly underlies the receiver 11 and the barrel 12, may be designated as a forestock-portion 10a, while the rear portion of the said stock, mainly to the rear of the receiver 11, may be designated as a buttstock-portion 10b.

Embracing the respective forward portions of the barrel-cap 13 and the forestock-portion 10a, is a front-band 14 of any suitable construction and which, in the instance shown, is provided on its left side (Fig. 1) with a vertical tubular socket 15 in which is pivotally mounted the adjacent ends of a loop or swivel 16 which may be conveniently formed of relatively-heavy steel wire and which is free to pivot in the usual manner of strap-loops or swivels.

Associated with the firearm in a manner as will be more fully hereinafter described, is a sling-strap generally designated by the reference character 17 which may be formed of textile material, leather or other suitable flexible materials. For purposes of description, the particular sling-strap 17 shown in the accompanying drawings may be considered to have a slide-end 18 and a coupling-end 19, the tip of which latter is preferably reinforced, as shown, by a metallic tip-guard 20. The slide-end 18 of the sling-strap 17 is preferably rigidly attached to one end of a slide-buckle 21, which is provided with a clamping-lever 22 in a manner generally common in slide-buckles.

Adjacent its tip-guard 20, the coupling-end 19 of the sling-strap 17 is formed with a longitudinally-extending slit-like buttonhole 23 through

which normally extends the rod-like shank 24 of a spool-shaped button 25. The rear portion of the shank 24 of the button 25 extends through a longitudinal slit-like buttonhole 26 formed in the coupling-end 19 of the strap a few inches inwardly from the buttonhole 23 before referred to, as is especially well shown in Figs. 2 and 3.

The coupling-end 19 of the sling-strap 17 is normally looped around a key-member 27 which preferably constitutes an adjunctive device or appurtenance useful in connection with the care of the firearm. In the particular instance shown, the key-member 27 is in the form of a cylindrical oil can comprising a vial-shaped body 28 normally having a knurled cap 29 threaded into its open end, which cap is formed with a slender stem or applicator 30 by means of which latter the oil within the body 28 may be applied to desired parts of the firearm-structure. The said key-member 27 is preferably formed of brass or other suitable non-rusting material of adequate mechanical strength.

Mainly in its left side, the buttstock-portion 10b of the stock 10 is formed with a longitudinally-extending groove-like recess or passage 31 comprising a tapering throat-portion 32 leading to the right side of the stock-portion 10b. The said throat-portion has side-walls 32a and 32b spaced from each other in a direction longitudinally of the stock 10 and sloping relatively steeply toward each other as they approach the right side of the buttstock-portion 10b. The side-walls 32a and 32b provide strap-seats, as will hereinafter appear, and they in effect face away from the right side of the stock 10 and toward the left face thereof.

The gap (in a horizontal direction) in the most contracted portion of the throat-portion 32 just above referred to, preferably has a horizontal dimension which is slightly in excess of the diameter of the key-member 27 plus one thickness of the sling-strap 17, but of a dimension smaller than the combined diameter of the said key-member 27 plus two thicknesses of the sling-strap 17, all for purposes as will more fully hereinafter appear. Leading forwardly from the widest part of the throat-portion 32 in the buttstock-portion 10b is a gently-sloping floor-portion 33 having its forward terminus gently merging into the contour of the left side of the buttstock-portion 10b, as is especially well shown in Fig. 8.

In its right side, the buttstock-portion 10b of the stock 10 is formed with a key-receiving recess or socket 34 relatively narrow in a direction lengthwise of the stock 10 and relatively long in a vertical direction. The vertical length of the key-receiving recess 34 just referred to exceeds the vertical width of the groove-like recess 31 before described and the central portion of the said key-receiving recess 34 intersects and is intersected by the said groove-like recess 31. As thus related to the recess 31, the key-receiving recess 34 has at each of its respective opposite ends one of two key-seats 35—35 which face outwardly toward the right side of the buttstock-portion 10b and hence away from the left side of the said buttstock-portion. The length of the key-receiving recess 34 is slightly in excess of the length of the key-member or oil can 27, and at its top and bottom ends respectively the said recess 34 is formed with one of two shallow clearance-channels 36—36 extending along both the front and rear side-walls, as well as the bottom wall, of the recess 34 to insure that the periphery of the overhanging cap 29 of the key-member 27

will be free of rubbing engagement with the stock, regardless of whether or not it is placed with its cap up or with its cap down.

One mode of assembling the sling-strap 17 with the firearm would be to first thread the coupling-end 19 of the said sling-strap through the swivel or loop 16 and then thread the said coupling-end through the slide-buckle 21 in a position beneath the clamping-lever 22 thereof, so that the intermediate portion of the sling-strap is looped around the swivel or loop 16, as is shown in Fig. 1. The coupling-end 19 of the sling-strap may now be inserted from left to right into the groove-like recess 31 in the left side of the buttstock-portion 10b and thence through the throat-portion 32 thereof and outwardly so as to project from the right side of the buttstock-portion 10b, as is shown by full lines in Fig. 3. The key-member 27 or its equivalent may now be laterally inserted from the right side of the buttstock-portion 10b into the key-receiving recess 34. The single thickness of the sling-strap will not bar the insertion of the key-member 27 since the horizontal dimensions of the minimum gap between the side-walls 32a and 32b of the throat-portion 32 is such that (as shown at A in Fig. 3) one thickness of the sling-strap may be simultaneously accommodated together with the key-member 27. When the key-member 27 is fully inserted into the key-receiving recess 34, as indicated by full lines in Fig. 3, the coupling-end 19 of the said sling-strap 17 may be reversely turned and passed from right to left back through the throat-portion 32 so as to pass to the rear of the key-member 27, as is indicated by the broken lines B in Fig. 3. The coupling-end 19 of the sling-strap 17 may now be swung into the position in which it is especially well shown in Fig. 2, and the buttonhole 23 therein slipped over the adjacent outer end of the spool-like button 25.

To disconnect the coupling-end 19 of the sling-strap 17 from the buttstock-portion 10b, the steps above described need merely to be reversed.

It is to be noted that when the coupling-end 19 of the sling-strap 17 is fully looped around the key-member 27 as is shown especially well in Fig. 2, neither the looped portion of the coupling-end 19 nor the key-member 27 itself may be moved from left to right out of the buttstock-portion 10b, since the throat-portion 32 of the groove-like recess 31 is too narrow to permit the key-member 27 plus two thicknesses of strap to pass from left to right. When strain is applied to the sling-strap 17, the key-member 27 will be pulled laterally both forwardly and to the left, with the result that the said key-member will be seated against the key-seats 35—35 and the front walls of the key-receiving recess 34.

As above described, the coupling-end 19 of the sling-strap 17 is prevented from being pulled out of the buttstock-portion 10b by the key-member 27 and conversely it is to be noted that the said key-member is restrained from being moved laterally out of the key-receiving recess 34 by the sling-strap 17. It will also be appreciated that by means of the construction shown, the oil can or key-member 27 is prevented from moving axially in a vertical direction in such manner as might release the coupling-end 19 of the sling-strap 17, by the respective upper and lower walls of the key-receiving recess 34.

By swinging the clamping-lever 22 of the slide-buckle 21 into its strap-freeing position, the slide-end 18 of the sling-strap 17 may be shifted along

the central or intermediate reach (showing on the outer face of Fig. 1) of the said sling-strap to either decrease or increase the amount of slack of the said sling-strap.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. A sling-strap firearm-structure including in combination: a stock having a first face and an opposite second face, the said stock being formed with a transverse passage leading from its said first face to its said second face, the said stock being also provided adjacent its said passage with key-seat means facing in a direction generally away from the said first face of the stock and positioned for engagement with a key-member; a key-member engaged with the said key-seat means adjacent the said passage through the stock; and a sling-strap extending inwardly from the said first face of the stock into the said passage therein and around the said key-member on the side thereof toward the said second face and thence reversely outwardly from the said passage toward the said first face of the stock.

2. A sling-strap firearm-structure including in combination: a stock having a first face and an opposite second face, the said stock being formed with a transverse passage leading from its said first face to its said second face, the said stock being also provided adjacent its said passage with key-seat means facing in a direction generally away from the said first face of the stock and positioned for engagement with a key-member; a key-member engaged with the said key-seat means adjacent the said passage through the stock; a sling-strap extending inwardly from the said first face of the stock into the said passage therein and around the said key-member on the side thereof toward the said second face and thence reversely outwardly from the said passage toward the said first face of the stock; and stop-means on the said stock located adjacent the key-seat means thereof in position to limit the movement of the said key-member in a direction parallel with the face of the said sling-strap.

3. A sling-strap firearm-structure including in combination: a stock having a first face and an opposite second face, the said stock being formed with a transverse passage leading from its said first face to its said second face and contracted adjacent the said second face of the stock to form a constricted throat-portion, the said stock being also provided adjacent its said passage with key-seat means facing in a direction generally away from the said first face of the stock and positioned for engagement with a key-member; a key-member engaged with the said key-seat means adjacent the said passage through the stock; and a sling-strap extending inwardly from the said first face of the stock into the said passage therein and around the said key-member on the side thereof toward the said second face and thence reversely outwardly from the said passage toward the said first face of the stock; the said key-member having a diameter which together with one thickness of the portion of the said sling-strap extending therearound is

less than the width of the throat-portion of the said passage in the stock, and the said key-member having a diameter which added to two thicknesses of the sling-strap extending therearound is greater than the width of the throat-portion of the said passage in the stock.

4. A sling-strap firearm-structure including in combination: a stock having a first face and an opposite second face, the said stock being formed with a transverse passage leading from its said first face to its said second face and contracted adjacent the said second face of the stock to form a constricted throat-portion, the said stock being also provided adjacent its said passage with key-seat means facing in a direction generally away from the said first face of the stock and positioned for engagement with a key-member; a key-member engaged with the said key-seat means adjacent the said passage through the stock; a sling-strap extending inwardly from the said first face of the stock into the said passage therein and around the said key-member on the side thereof toward the said second face and thence reversely outwardly from the said passage toward the said first face of the stock; and stop-means on the said stock located adjacent the key-seat means thereof in position to limit the movement of the said key-member in a direction parallel with the face of the said strap; the said key-member having a diameter which together with one thickness of the portion of the said sling-strap extending therearound is less than the width of the throat-portion of the said passage in the stock, and the said key-member having a diameter which added to two thicknesses of the sling-strap extending therearound is greater than the width of the throat-portion of the said passage in the stock.

5. A sling-strap firearm-structure including in combination: a stock having a first face and an opposite second face, the said stock being formed in its said second face with a key-receiving recess having key-seat means facing generally away from the said first face of the stock, the said stock also being formed with a transverse passage leading from its said first face laterally into communication with the key-receiving recess in the said second face of the stock; a key-member located in the said key-receiving recess of the stock in engagement with the said key-seat means thereof; and a sling-strap extending inwardly from the said first face of the stock into the said passage therein and around the said key-member on the side thereof toward the said second face and thence reversely outwardly from the said passage toward the said first face of the stock.

6. A sling-strap firearm-structure including in combination: a stock having a first face and an opposite second face, the said stock being formed in its said second face with a key-receiving recess having key-seat means facing generally away from the said first face of the stock, the said stock also being formed with a transverse passage leading from its said first face laterally into communication with the key-receiving recess in the said second face of the stock; a key-member located in the said key-receiving recess of the stock in engagement with the said key-seat means thereof; a sling-strap extending inwardly from the said first face of the stock into the said passage therein and around the said key-member on the side thereof toward the said second face and thence reversely outwardly from the said passage toward the said first face of the stock; and

stop-means on the said stock located adjacent the key-seat means thereof in position to limit the movement of the said key-member in a direction parallel with the face of the said sling-strap.

7. A sling-strap firearm-structure including in combination: a stock having a first face and an opposite second face, the said stock being formed in its said second face with a key-receiving recess having key-seat means facing generally away from the said first face of the stock, the said stock also being formed with a transverse passage leading from its said first face laterally into communication with the key-receiving recess in the said second face of the stock and contracted adjacent the said second face to form a constricted throat-portion; a key-member located in the said key-receiving recess of the stock in engagement with the key-seat means thereof; and a sling-strap extending inwardly from the said first face of the stock into the said passage therein and around the said key-member on the side thereof toward the said second face and thence reversely outwardly from the said passage toward the said first face of the stock; the said key-member having a diameter which together with one thickness of the portion of the said sling-strap extending therearound is less than the width of the throat-portion of the said passage in the stock, and the said key-member having a diameter which added to two thicknesses of the sling-strap extending therearound is greater than the width of the throat-portion of the said passage in the stock. *

8. A sling-strap firearm-structure including in combination: a stock having a first face and an opposite second face, the said stock being formed in its said second face with a key-receiving recess having key-seat means facing generally away from the said first face of the stock, the said stock also being formed with a transverse passage leading from its said first face laterally into communication with the key-receiving recess in the said second face of the stock and contracted adjacent the said second face to form a constricted throat-portion; a key-member located in the said key-receiving recess of the stock in engagement with the key-seat means thereof; a sling-strap extending inwardly from the said first face of the stock into the said passage therein and around the said key-member on the side thereof toward the said second face and thence reversely outwardly from the said passage toward the said first face of the stock; and stop-means on the said stock located adjacent the said key-seat means thereof and positioned to limit the movement of the said key-member in a direction parallel with the face of the said sling-strap; the said key-member having a diameter which together with one thickness of the portion of the said sling-strap extending therearound is less than the width of the throat-portion of the said passage in the stock, and the said key-member having a diameter which added to two thicknesses of the sling-strap extending therearound is greater than the width of the throat-portion of the said passage in the stock.

9. A sling-strap firearm-structure including in combination: a stock having a first side-face and an opposite second side-face, the said stock being formed with a transverse passage leading from its said first side-face to its said second side-face, the said stock being provided adjacent its said second side-face with two key-seats one of which is located above the said passage and the

other being located below the said passage and both thereof facing in a direction generally away from the said first side-face of the stock; a key-member having a vertical dimension exceeding the vertical dimension of the said passage in the stock and resting adjacent its respective opposite ends upon the aforesaid key-seats of the stock; and a sling-strap extending inwardly from the said first side-face of the stock into the said

10 passage therein and around the key-member on the side thereof toward the said second side-face and thence reversely outwardly from the said passage toward the said first side-face of the stock.

15 10. A sling-strap firearm-structure including in combination: a stock having a first side-face and an opposite second side-face, the said stock being formed with a transverse passage leading from its said first side-face to its said second side-face, the said stock being provided adjacent its said second side-face with two key-seats one of which is located above the said passage and the other being located below the said passage and both thereof facing in a direction generally away

20 25 from the said first side-face of the stock; a key-member having a vertical dimension exceeding the vertical dimension of the said passage in the stock and resting adjacent its respective opposite ends upon the aforesaid key-seats of the stock; a sling-strap extending inwardly from the said first side-face of the stock into the said passage therein and around the key-member on the side thereof toward the said second side-face and thence reversely outwardly from the said passage toward

30 35 the said first side-face of the stock; and two stop-abutments one of which is located adjacent each of the respective key-seats of the said stock in position to limit the vertical movement of the said key-member.

40 45 11. A sling-strap firearm-structure including in combination: a stock having a first side-face and an opposite second side-face, the said stock being formed with a transverse passage leading from its said first side-face to its said second side-face and contracted adjacent the said second side-face of the stock to form a constricted throat-portion, the said stock being provided adjacent its said second side-face with two key-seats, one of which is located about the said passage and the other being located below the said

50 55 passage and both thereof facing in a direction generally away from the said first side-face of the stock; a key-member having a vertical dimension exceeding the vertical dimension of the said passage in the stock and resting adjacent its respective opposite ends upon the aforesaid key-seats of the stock; and a sling-strap extending inwardly from the said first side-face of the stock into the said passage therein and around

60 65 the key-member on the side thereof toward the said second side-face and thence outwardly from the said passage toward the said first side-face of the stock; the said key-member having a horizontal dimension intermediate its respective opposite ends which together with one thickness of the portion of the said sling-strap extending therearound is less than the width of the throat-portion of the said passage in the stock, and the

70 75 said key-member having a diameter which added to two thicknesses of the sling-strap extending therearound is greater than the width of the throat-portion of the said passage in the stock.

12. A sling-strap firearm-structure as defined in claim 11 and in which the said stock is formed with two substantially-horizontal clearance-

channels, one of which is located above the upper of the two said key-seats in the stock and the other clearance-channel being located below the lower of the two said key-seats in the stock.

13. A sling-strap firearm-structure including in combination: a stock having a first side-face and an opposite second side-face, the said stock being formed with a transverse passage leading from its said first side-face to its said second side-face and contracted adjacent the said second side-face of the stock to form a constricted throat-portion, the said stock being provided adjacent its said second side-face with two key-seats, one of which is located above the said passage and the other being located below the said passage and both thereof facing in a direction generally away from the said first side-face of the stock; a key-member having a vertical dimension exceeding the vertical dimension of the said passage in the stock and resting adjacent its respective opposite ends upon the aforesaid key-seats of the stock; a sling-strap extending inwardly from the said first side-face of the stock into the said passage therein and around the key-member on the side thereof toward the said second side-face and thence reversely outwardly from the said passage toward the said first side-face of the stock; and two stop-abutments, one of which is located adjacent each of the respective key-seats of the said stock in position to limit the vertical movement of the said key-member, the said key-member having a horizontal dimension intermediate its respective opposite ends which together with one thickness of the portion of the said sling-strap extending therearound is less than the width of the throat-portion of the said passage in the stock, and the said key-member having a diameter which added to two thicknesses of the sling-strap extending therearound is greater than the width of the throat-portion of the said passage in the stock.

14. A sling-strap firearm-structure including in combination: a stock having a first side-face and an opposite second side-face, the said stock being formed in its said first side-face with a strap-receiving recess leading laterally toward the said second side-face of the stock, the said stock also being formed in its said second side-face with a key-receiving recess having a vertical dimension exceeding the vertical dimension of the said strap-receiving recess and intersecting the latter, the said stock being formed in its said key-receiving recess with two key-seats one of

which is located above the said strap-receiving recess and the other being located below the same and both thereof facing in a direction generally away from the said first side-face of the stock; a key-member having a vertical dimension exceeding the vertical dimension of the said strap-receiving recess in the stock and resting adjacent its adjacent opposite ends upon the aforesaid key-seats of the said stock; and a sling-strap extending inwardly from the said first side-face of the stock into the said strap-receiving passage therein and around an intermediate portion of the said key-member on the side thereof toward the said second side-face of the stock and thence reversely outwardly from the said strap-receiving recess toward the said first side-face of the stock.

15. A sling-strap firearm-structure including in combination: a stock having a first side-face and an opposite second side-face, the said stock being formed in its said first side-face with a strap-receiving recess leading laterally toward the said second side-face of the stock, the said stock also being formed in its said second side-face with a key-receiving recess having a vertical dimension exceeding the vertical dimension of the said strap-receiving recess and intersecting the latter, the said stock being formed in its said key-receiving recess with two key-seats, one of which is located above the said strap-receiving recess and the other being located below the same and both thereof facing in a direction generally away from the said first side-face of the stock; two stop-abutments one of which is located above the upper key-seat in the said stock and the other of which is located below the lower key-seat in the said stock respectively in position to limit the upward and downward movement of the key-member; a key-member having a vertical dimension exceeding the vertical dimension of the said strap-receiving recess in the stock and resting adjacent its adjacent opposite ends upon the aforesaid key-seats of the said stock; and a sling-strap extending inwardly from the said first side-face of the stock into the said strap-receiving passage therein and around an intermediate portion of the said key-member on the side thereof toward the said second side-face of the stock and thence reversely outwardly from the said strap-receiving recess toward the said first side-face of the stock.
